PNEUMATICALLY ACTUATED ANTOVER-FLOW ALARM AND SAFETY DEVICE FOR TANKERS

Harry Liles, Yeadon, Pa.

Application May 29, 1952, Serial No. 290,699

4 Claims. (Cl. 340—244)

1

This invention relates primarily to a means for avoiding overflow of the individual tanks of oil tanker vessels during the loading operation, and a principal object of the invention is to provide a device of this character comprising a suitable signal or alarm responsive to an abnormally high liquid level in any one of the tanks of the vessel whereby the pumping of the oil to the tanks, or to the particular tank wherein overflow is threatened, may be interrupted in due time.

Another object of the invention is to provide a device of the stated character comprising a fluid system associated with a plurality or all of said tanks and operatively connected with a common alarm or signal device.

A further object is to provide a safety device of the stated character which will function also as a means for signalling the presence in any of the tanks of abnormally high pressures.

Still another object of the invention is to provide a device of the stated character having readily accessible means for checking the operativeness of the elements of the apparatus.

The invention resides also in certain mechanical and structural details, hereinafter described and illustrated in the attached drawings, wherein:

Figure 1 is a diagrammatic cross-sectional view of a typical oil tanker;

Figure 2 is an enlarged diagrammatic elevational and partial sectional view illustrating details of the anti-overflow and pressure alarm system shown in Figure 1;

Figure 3 is an enlarged sectional view illustrating a detail of the apparatus shown in Figure 2, and

Figure 4 is a diagrammatic sectional view illustrating a modification within the scope of the invention.

Oil tanker vessels are conventionally divided by suitable bulkheads into a number of individual compartments or tanks, and it is customary to provide also a supply pipe system which extends to all of the individual tanks and through which the tanks may be simultaneously filled with the oil cargo pumped through the system from an external supply source. Each of the tanks is provided with a man-hole at the top by which access may be had to the interior of the tank from the deck of the vessel; and each man-hole cover is usually provided with a small opening having a detachable cover and constituting what is known as a "ullage" hole through which the interior of the tank may be inspected to determine the level of the oil in that particular tank at any

instant. It has been found that the rate of charge in the various tanks, while theoretically the same, is actually subject to relative variation by reason of different local conditions affecting the oil flow, so that in loading the level of the oil in one tank cannot be used as an index of the level in the other tanks. In the larger tankers particularly, the number of individual tanks is so great that constant inspection of all of the tanks by way of the "ullage" holes during the filling operation is not feasible, and it frequently occurs that one or more of the tanks will fill to overflow in the interval of time between successive inspections of that tank. Since such overflow is highly undesirable by reason of resulting harbor contamination and the very real fire hazard involved in the presence of oil on the deck of the tanker, it is of importance that overflow be avoided if possible. Such avoidance is the primary object of the present invention.

With reference to the drawings, the numeral 1 indicates the hull of a typical oil tanker which, in accordance with the usual practice, contains a series of transverse bulkheads, of which one is indicated at 2, and one or more longitudinal bulkheads indicated in the present instance at 3 and 4 respectively, which bulkheads divide the interior of the vessel into a number of individual tanks for the oil cargo. Each of the tanks is provided at the top with a man-hole 5 and each man-hole cover 6 is provided with an opening normally closed by a detachable cover 7, this hole, known as the "knowledge" hole, being provided for the purpose of inspection to determine the level of the oil in the tank.

Manifold pipes 11, 12 and 13 extend longitudinally of the vessel through the respective longitudinal rows of tanks, and these pipes conventionally constitute elements of a single system through which oil is pumped from external source to the individual tanks of the vessel. The pipes 11, 12 and 13 communicate with the individual tanks by means of branch ducts 14, 15 and 16 and each of these ducts contains a valve 17 by means of which the duct may be opened or closed, or restricted, as may be found desirable. The valves 17 are actuated manually by way of valve rods 18 which extend upwardly to the top of the tank, the upper ends of the rods being accessible through independent openings, not shown, in the top wall or deck 19. By this means each of the tanks may be individually connected or disconnected from the oil supply source and the rate of filling may be regulated as may be found desirable.

In accordance with the present invention I provide in the top of each of the tanks an inverted cup or bell, indicated in Figure 1 by the reference numerals 21, 22 and 23 respectively. A duct 24, 25 and 26 respectively extends from the top of each of these bells to a fitting designated generally by the reference numeral 27 and in the present instance the three fittings associated with the individual tanks 28, 29 and 31 shown in Figure 1 are mounted in a housing 32 located in a suitable position above the deck 19 externally of the tanks. The fittings 27 are of the form illustrated in Figure 3, wherein it will be noted that the duct 24, in this instance, communicates with a vertical hollow stem 33 having in the upper portion thereof a seat 34 for a spherical check valve 35. This valve is confined in a chamber in the top of the stem 33 by a screw plug 36 which may be removed to afford access to the valve element. The side walls of the valve chamber are provided with ports 37 which when the ball valve 35 is unseated establish communication between the duct 24 and chamber 38 in the interior of the fitting 27. This chamber embraces the stem 33 and access to the chamber and to the stem may be had by removal of a screw cap 39 at the top of the fitting. The chamber 38 has ports at opposite sides and through these ports the chamber of each of the fittings is connected with the chamber of the other fittings of the group by way of nipples 41. The port 42 of one of the terminal fittings 27 is provided with a hollow plug 43 containing a valve 44 whereby the chamber 38 may be connected with an external source of air pressure, not shown, or with the atmosphere for purposes hereinafter described. The port 45 of the fitting 27 at the opposite end of the group is connected by way of a tube 46 with a Sylphon bellows 47. This bellows is connected to a lever 48 pivoted at 49 and operatively connected at its opposite end, by way of an adjustable pin 51, with the actuating element of a suitable switch 52. This switch controls and electric circuit 53 containing an electric alarm or signal bell 54.

In the operation of this device it will be apparent that when the level of oil in the tanks, or in any one of the tanks, reaches the bottom of the associated bell, 21, 22 or 23 as the case may be, the continued flow of oil into the tank will place the air trapped within the bell under a continuously increasing pressure. This pressure elevates the ball valve 35 of the associated fitting 27 and permits displacement of air from the bell through the ports 37, the chamber 38, and the tube 46 to the bellows 47. This results in an immediate expansion of the bellows and a tripping of the switch 52 with resultant sounding of the alarm. The entire loading operation may then be interrupted or, if the critical tank has been located, that tank may be disconnected from the supply source by closure of the associated valve 17. The extra air in the system which caused the expansion of the Sylphon 47 may then be exhausted by opening of the valve 44 to bleed the system, thereby returning the Sylphon 47 to its original position and placing the system in condition for subsequent operation in the event that another of the tanks becomes full before the others.

It will be noted that by reason of the location of the bells 21, 22 and 23 in the upper portions of the tank, the device is normally unaffected until the liquid level in one or more of the tanks has risen to an abnormal position,

it being understood that each of the tanks is vented at the top so as to permit escape of air from the upper areas of the tank to the atmosphere as the air is displaced by the oil entering the tank. The device is highly sensitive in that it operates almost immediately after the level of the liquid has covered the open bottom of the bell.

The device is also operative to sound the alarm 54 in event of clogging of the vent in any of the tanks and the resulting increase in the pressure within the tank due to the injected oil. This is an important phase of the invention in that it prevents development of dangerous pressures in the individual tanks which might under certain conditions cause rupture of a bulkhead.

The device described above provides also for a thorough check of the anti-overflow system to give assurance that all parts of the system are in proper functioning condition. Each of the check valves 35 may be inspected by removal of the cap 39 of the associated fitting 27 and of the plug 36. By removal of the valve 35 compressed air may be injected through the stem 33 and duct 24 to make sure that the passages are clear and unobstructed. After replacement of the valve and of the cap 39 application of pressure air to the system may be effected by way of the fitting 43, and if the several valves are in order the resulting elevation of pressure in the system will sound the alarm and thereby indicate that the system is in proper working condition.

For the purpose of simplification, I have described the invention in terms of the three tanks of a transverse group. It will be understood, however, that the invention contemplates the inclusion of all the tanks in a common system and this is accomplished in the present instance by connecting each of the transverse groups of tanks with the other transverse groups through a manifold 55 which extends the full length of the vessel and which is connected with the common alarm which includes the Sylphon 47 and bell 54. The switch 52 may be of any desired type of adequate sensitiveness, but a switch of the mercury bulb type is desirable by reason of its non-sparking characteristic.

In the aforescribed embodiment of my invention the check valves 35 associated with the respective tanks are essential in order that the air displaced by the rising oil in one or more of the bells will pass to the Sylphon 47 instead of back into the bells of the other tanks. In Figure 4 I have illustrated a system by which the valves may be eliminated. In this case, each of the bells is provided at the top with an imperforate flexible diaphragm 56 which is backed on the underside in the present instance by a perforated plate 57. The diaphragm forms a chamber 58 in the extreme top of the bell which is separated from the main chamber of the bell below the plate 51. The chamber 58 is connected through a suitable duct 59 with a Sylphon 61 which is associated with a suitable signal or alarm of the character previously described and illustrated in Figure 2 of the drawings. The Sylphon 61 and the pipe system connecting this Sylphon with the chamber 58 of the bell, and the chamber 58 itself, is filled with a suitable liquid so that any increase in air pressure in the lower portion of the bell resulting from the rising oil level will result in an upward displacement of the diaphragm 56 and a displacement of the liquid from the chamber 58 to

the Sylphon 61, thus sounding the alarm. Each of the bells of the several tanks will be similarly connected by a common liquid system to the Sylphon 61 in obvious manner, it being apparent that the displacement of liquid resulting from the elevation of one of the diaphragms 56 must manifest itself in an expansion of the Sylphon 61 by reason of the support of the diaphragms of the other bells by the associated perforated plates 57. While this embodiment of the device is relatively simple by reason of its elimination of the valves 35 of the other embodiments, it does not lend itself as readily to check for operativeness. It will be apparent, however, that means can readily be provided for insuring that the system is in operative condition.

While having an application of particular value to oil tank vessels as described above, the invention is applicable also to oil storage tanks wherein it may be usefully employed to provide warning against overflow and against development within one or a number of tanks of excessive pressures, all in accordance with the previously described principle.

I claim:

1. In an anti-overflow device for the several tanks of an oil tank vessel, an inverted cup in each of said tanks located so that its lower edge adjoins the normal upper level of oil in the tank, a pneumatic system connected with the upper ends of all of said cups and including a displaceable element responsive to abnormal pressure within said system, signal means operatively connected to said element, and a check valve con-

trolling the connection between each of said cups and said system, said valves permitting displacement of air from the cups to the system but precluding a displacement in the opposite direction.

5 2. An anti-overflow device according to claim 1 wherein the said check valves are located so as to be accessible from the exteriors of the tank.

10 3. An anti-overflow device according to claim 2 wherein the said check valve comprises a casing having a releasable access opening providing for inspection of the valve structure.

15 4. An anti-overflow device according to claim 3 wherein the system comprises a port intermediate the said valves and the displaceable element and releasable means for normally sealing said port, said port affording access to the system for application to the latter of pressure fluid and for bleeding the system of excess air pressure.
